UNITED STATES PATENT OFFICE

2,581,426

ARRANGEMENT FOR RECEIVING
TELEGRAPH IMPULSES

Frederick Percival Mason, Croydon, England, assignor to Creed and Company Limited, Croydon, England, a British company

Application December 13, 1946, Serial No. 716,150
In Great Britain March 24, 1939Section 1, Public Law 690, August 8, 1946
Patent expires March 24, 1959

6 Claims. (Cl. 178—33)

1

This invention relates to a receiving arrangement for a printing telegraph system using combinations of impulses, each impulse consisting of one of two different line conditions known as marking and spacing conditions existing during a definite interval of time.

When received, the impulses may have become distorted so that the appropriate condition, marking or spacing, does not persist throughout the whole of the time interval allotted thereto. In order to permit signals with the largest possible distortion to be received correctly, it is customary to read the signals, as shown by the position of the armature of the receiving relay, in the middle of the interval allotted to each signal impulse. The theoretical duration of a printing telegraph signal impulse in the five-unit code is 20 milliseconds at a speed of 50 bauds. The maximum theoretical margin of a receiving arrangement is limited in part by the relay transit time which may be 0.5 milliseconds and in part by the minimum duration of time during which it is possible to read the condition of the line, which may be 1.5 milliseconds. The line reading time thus causes a loss of margin of 7½% at a speed of 50 bauds, and this is raised to 8¼% at a speed of 55 bauds.

The object of the present invention is to eliminate the time necessary for reading the nature of a signal impulse over and above the transit time of the line relay.

The invention depends upon receiving a code combination by means which detects changes of condition in a line between successive elements of a code combination. The nature of the invention will be better understood from the following description taken in conjunction with the accompanying drawings, of which:

Figs. 1 to 4 illustrate different arrangements according to the invention as applied to receiving arrangements for the well known five-unit code. In each of these arrangements instead of the usual arrangement in which the time devoted to each character is divided into five intervals of equal duration each of which should be occupied by one of two different conditions, the time devoted to each character is regarded as containing five intervals of equal duration, at the midpoint of each of which a change in condition of the line may take place. In these arrangements, the change of condition of the line may, owing to distortion, be displaced up to 10 milliseconds (for a speed of 50 bauds) in either early or late direction.

Referring to the drawings all the arrangements

2

shown are of a generally similar character and are adapted for receipt of signals according to the start-stop system. In each arrangement a series of contacts C1—C6 is provided, contact C6 of which is normally closed whilst contacts C1—C5 are adapted to be closed in succession by means of a rotating shaft started into rotation by the energisation of a magnet M. Each of the contacts C1—C5 remains closed for a period of 20 milliseconds at the middle of which the change in condition of the line should take place if the signals are undistorted. The changes in condition of the line are then stored on five condensers K1—K5, the charges on which are afterwards connected to the grids of three-electrode gas-filled tubes T1—T5 so that a discharge is initiated in such of the tubes as are connected to condensers that have been charged. The anode circuits of these tubes are connected to a translating device. This device may comprise magnets or relays which carry out a translation of the combination of impulses by positioning a type carrier or like device in any well known manner. By like device is to be understood a device which instead of being itself a type carrier selects the position of a type bar for actuation. For simplicity in what follows it will be assumed that a typewheel is positioned. Such typewheel may be positioned in accordance with the currents in the anode circuits of the tubes T1—T5 by means of the arrangements described and claimed in British Patent No. 499,209.

It must, however, be noted that the particular code combination of current or absence of current in the anode circuits of tubes T1—T5 is not the same code combination of marking and spacing conditions as is received. It is thus necessary to alter the order of the characters on the typewheel positioned by the translating device from that representing the ordinary five-unit code to that representing the new code.

Referring now to Fig. 1, this represents the simplest arrangement according to the invention. The line L over which signals are received is connected to a receiving relay A. The armature a of relay A is adapted to operate between marking and spacing contacts m and s which are connected together and to ground. Whilst the armature a is resting on one of its contacts, a current passes from positive battery B6 through a resistance R3, the armature a and the contact to ground. As stated above, contacts C6 are normally closed so that when the armature a leaves its marking contact m in response to the start element of a signal combination, the po-

3

tential from the battery B_6 is connected over resistance R_3 , a rectifier MR_3 , which is preferably a metal rectifier and contacts C_6 to the grid of a three-electrode gas-filled thermionic tube T_6 , the grid of which is normally kept at a slight positive potential by being connected to the positive pole of battery B_8 through resistance L_6 . The potential normally connected to the grid of tube T_6 is insufficient to initiate a discharge in the tube but when the potential of battery B_6 is connected to the grid, a discharge in the tube is initiated and magnet M connected in the anode circuit of the tube is energized and starts into rotation the shaft controlling the various contacts of the receiving arrangement. Contacts C_1 — C_5 are operated in sequence and if, during the interval when any one of these contacts is closed, a transit of the armature a between marking and spacing or between spacing and marking contact occurs, the potential of battery B_6 is connected through resistance R_3 , the rectifier MR_3 and the particular contacts that are closed to one side of one of the condensers K_1 — K_5 , the other side of which is connected to ground. Contacts C_6 are opened shortly after the commencement of rotation of the shaft and before the termination of the period of rotation of the shaft contacts C_{11} — C_{15} are closed and the negative pole of a battery B_7 is connected to the grid of tube T_6 to extinguish the discharge therein. Immediately after the opening of contacts C_5 contacts C_{11} — C_{15} are closed and connect one side of the condensers K_1 — K_5 to the grids of the five tubes T_1 — T_5 . These grids are normally connected over the grid leak resistance GR_1 — GR_5 to the negative pole of batteries B_1 — B_5 , so that the tubes are normally quiescent. When, however, the condensers are connected to the grids of the tubes, those condensers that are charged will initiate a discharge in their corresponding tubes and the consequent currents in the anode circuits of these tubes are utilised as described above. Contacts C_{11} and C_{15} are opened again before the shaft comes to rest and contacts C_{11} to C_{15} are closed. Leak resistances L_1 — L_5 are provided in shunt to the respective condensers K_1 — K_5 so that should the charge on any charged condenser not be completely discharged during its connection to the grid of its corresponding tube, and should it also not be recharged before its next connection to its corresponding grid the charge will leak away. The shaft controlling the contacts shown may start into rotation a further shaft controlling the printing action, or may close a contact to operate a printing magnet.

In the arrangement above described any interference in the line or bounce of the relay armature that momentarily separates the fixed and moving contacts of the receiving relay gives an effect similar to the effect of a transit and such an arrangement could therefore only be used with a well adjusted relay connected to a line free from interference. This drawback is avoided in the arrangement shown in Fig. 2. In this arrangement the armature a of the line relay A is operated by a coil connected in the line L , but is also wound with a coil b in which an impulse is generated at each movement of the armature. As the direction of the generated impulse current depends upon the direction of transit, rectifiers MR_1 , MR_2 are provided to obtain a positive impulse for either direction of transit of the armature. In this arrangement the circuits can be so arranged that a partial movement of

4

the armature does not provide sufficient energy to operate the gas-filled tubes T_1 — T_6 . In the modification shown in Fig. 3 the impulses generated in the coil b by the movement of the armature charge a condenser K_6 through a full wave rectifier bridge MR_8 , MR_9 , MR_{10} , MR_{11} . At the moment when the line relay contacts m or s close at the end of the armature travel the condenser K_6 is connected through the armature and either the marking or spacing contacts m and s and the rectifier MR_3 to charge up the particular capacity K_1 — K_5 that is at the moment connected. The effect of this arrangement is to reduce the effective line reading time to the time of discharge of the condenser K_6 . An inductance L_7 may be connected in series with the condenser K_6 and may be so proportioned that the discharge time of the condenser coincides with half the period of the frequency to which condenser K_6 and inductance L_7 are tuned. This increases the amount of the charge transferred by virtue of the oscillatory action. In the arrangement shown in Fig. 4 the use of a line relay is obviated, but line L is connected to one diagonal of a full wave rectifier bridge MR_4 , MR_5 , MR_6 , MR_7 across the other diagonal of which is connected a resistance R_4 . Any continuing condition of the line produces a unidirectional potential across R_4 in opposition to the steady potential derived from a tapping on the potentiometer P across the battery B_6 . At those instants when the current in the line L passes through zero, this opposing potential becomes zero and the potentiometer P can supply a charge to whichever condenser K_1 — K_5 is connected to the common circuit g . This arrangement, however, is only adapted to receive double current signals.

Although in the above described arrangements a change in condition of the line results in a charge upon the corresponding condenser of the condensers K_1 — K_5 , it is clear that the circuits could equally well be arranged so that a charge on the condenser corresponded to an absence of change of condition in the line.

What is claimed is:

1. Receiving arrangement for a printing telegraph system comprising means for registering consecutive changes in the electrical condition of a signal line during reception over the line of a signal consisting of a series of consecutive elements each represented by a line condition, said means including a relay connected to said line and actuated by said changes, the relay having an armature shifted between two contacts by each such change, a signal registering unit including a plurality of registering elements, an operating circuit for said elements connected to the armature means for rendering the operating circuit effective only when the armature is out of engagement with said contacts, and means for connecting the operating circuit to said registering elements in succession during the periods of change-over from one signal element to the next; and means controlled by the registering means for producing corresponding simultaneous changes in the electrical conditions of a plurality of printing telegraph control lines.

2. An arrangement as claimed in claim 1 in which the operating circuit includes a current source, and each registering element includes a device actuated by current from said source.

3. An arrangement as claimed in claim 2 in which said device is a condenser charged by said current.

4. An arrangement as claimed in claim 1 in which the means for rendering the operating circuit effective includes a current generating device actuated by movement of the armature.

5. Receiving arrangement for a printing telegraph system comprising means for registering consecutive changes in the electrical condition of a signal line during the reception over the line of a code signal consisting of a series of consecutive elements each represented by a line condition, said means operable between successive elements of the code signal, said means including a relay connected to said line and actuated by said changes, the relay having an armature shiftable between two contacts by each such change, a signal registering unit and means for operating said unit to register a signal element when said armature is shifted, said last named means including an operating circuit connected to said armature, means for rendering said circuit effective only when the armature is out of engagement with said contacts, and means controlled

by said registering means for producing corresponding simultaneous changes in the electrical conditions of a plurality of printing telegraph control lines.

5 6. An arrangement as claimed in claim 5 in which the latter means includes a shunt circuit for the operating circuit connected to said contacts.
